DESIGN FOR A COMBINATION DESK SET

Carey G. Gregory, Los Angeles, Calif.

Application November 14, 1936, Serial No. 65,915

Term of patent 14 years

To all whom it may concern:

Be it known that I, Carey G. Gregory, a citizen of the United States, residing at Los Angeles, in the county of Los Angeles and State of California, have invented a new, original, and ornamental Design for a Combination Desk Set, of which the following is a specification, reference being had to the accompanying drawing, forming part thereof:

Fig. 1 is a front elevational view of a combination desk set showing my new design;

Fig. 2 is an end view thereof; and

Fig. 3 is a top plan view.

I claim:

The ornamental design for a combination desk set, as shown.

CAREY G. GREGORY.
